(57) CLAIM

The ornamental design for a Christmas window light, as shown and described.

DESCRIPTION

FIG. 1 is a front perspective view of a Christmas window
light, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof, shown in a used condition with string lights shown in broken lines.

The broken lines in the drawings illustrate the portions of the Christmas window light, which form no part of the claimed design.

1 Claim, 6 Drawing Sheets
